RAILWAY SIGNALING SYSTEM

Joaquín Rosell, Barcelona, Spain, assignor to
General Railway Signal Company, Rochester,
N. Y.

Application April 23, 1932, Serial No. 607,111

13 Claims. (Cl. 246—33)

This invention relates to railway signaling systems of the absolute-permissive-block type, and more particularly to the application of a quick acting spectacle type light signal operated by currents of distinctive character applied to such a system.

An absolute-permissive-block signaling type system is one wherein trains may follow each other with the usual spacing of trains and signal protection as afforded in one way traffic signaling, with the additional protection of permitting trains to move only in one direction in a particular stretch of track at one time.

Other objects, purposes and characteristic features of the present invention will in part be apparent from the accompanying drawing and will in part be more specifically pointed out herein-after.

In describing the invention in detail, reference will be made to the accompanying drawing, in which:

Fig. 1 shows an intermediate portion of a single track section in which one of the signals has been shown controlled and wired in accordance with the present invention; and

Figs. 2, 3 and 4 illustrate a light signal of the quick acting spectacle type in the clear, danger and caution positions, respectively.

Referring to the drawing, the track rails 1 have been shown divided into blocks by insulating joints 2, of which the block I and the adjacent ends of two other blocks H and J only have been illustrated. Each of these blocks preferably constitutes a central fed track circuit, which for the block I includes a transformer TR connected across the track rails 1 at an intermediate point in a block, which transformer feeds the track relays T² and T⁶.

Referring to Fig. 1, although the spectacle type light signal may be of any suitable construction, and may be operated by polar circuits supplying either alternating current of different relative polarities or direct current of different polarities depending on its construction, and may include contacts operated by the motor of such light signal of varied designs, a signal S⁶ has been shown operated by a motor of the induction type including the rotor RW, a local field winding LW⁶ and a control field winding CW⁶. This signal is preferably one of the focused beam or search-light type, wherein light rays come to a focus between the reflector and lens thereof with a spectacle or movable color screen traversing the beam near said focus so that the spectacle color glasses may be

very small and require very little power for operation thereof.

Each of the light signals S³, S⁴, S⁵ and S⁶ includes a spectacle SP, containing color screens or filters G, Y and R to transmit lights colored green, yellow and red, respectively. Each of these light signals also includes a lamp L, which may be energized continuously, or may be energized in accordance with suitable approach lighting circuits well known in the art.

The light beam emitted by the light signal is derived from the lamp L and is colored green, yellow or red depending upon whether the spectacle assumes the clear, the caution or the danger position. The light signals under consideration include contacts 10 and 11 operated by the rotor RW, and these contacts both assume their biased position, as shown in Fig. 3, when the signal motor is deenergized. The contact 10 only assumes its operated position (see Fig. 4), when the signal assumes the caution position, and the contact 11 only assumes its operated position (see Fig. 2), when the signal mechanism assumes the clear position.

In addition to the apparatus already mentioned, each signal location includes a pole changer relay PC and a stick relay S, which relays have been designated 6PC and 6S, respectively, for the signal location including signal S⁶. Each of these signal locations also includes a transformer, of which the transformer for the signal location under consideration has been designated 12 and has its primary winding connected to a source of alternating current AC.

Operation

Under normal clear traffic conditions, the winding CW⁴ of the signal S⁴ is energized through the following circuit:—beginning at the upper terminal of the secondary winding of the transformer 12, wire 13, front contact 14 of the pole changer relay 6PC, wire 14—A, contact 14—A¹ of the stick relay 6S (associated with the signal S⁶), wire 15, contact 16 of the track relay T⁶, wire 17, back contact 18 of the stick relay 6S (associated with the signal S³), wire 19, front contact 20, wire 21 of the track relay T², winding CW⁴, wire 22, common return wire C and wire 23 to the midpoint of the secondary winding of transformer 12. The winding CW⁶ is energized by a similar circuit, shown only in part, and including the contacts 18¹ and 20¹ of relays 6S and T⁶, respectively. The local winding LW⁶ is energized directly from the secondary winding of the transformer by a circuit not shown in

the drawing. The currents in these two circuits are in practice displaced in phase so as to produce a torque in the rotor RW. The signal S⁶, therefore, assumes its clear position, as does also the signal S⁴. With the signal S⁶ in its clear position the contact 11 of this signal is closed, thus energizing the pole changer relay 6PC through the following circuit:—beginning at the terminal B, contact 11 of signal S⁶, wire 24, winding of the relay 6PC to the other terminal C of said battery.

Let us assume that there is a west-bound train moving in the single track section shown, and that this train has by its entrance into the single track section caused the tumble-down arrangement including the various circuits for the windings CW of the various signals governing east-bound traffic to be opened sequentially. That is, the entrance of the west-bound train into the single track section effected deenergization of the winding CW⁶ of signal S⁶, thereby causing the signal S⁶ to assume its deenergized position, allowing the return of the contact 11 to its biased position and effecting deenergization of the relay 6PC. After a short period of time, the relay 6PC being slow dropping, its front contact 14 is opened, thereby effecting deenergization of the circuit for the winding CW⁴ of the signal S⁴. Back contact 14 does not reclose the circuit in question because front contact 40 of relay 6S is open. In the same way as explained for the signals S⁶ and S⁴, all of the signals governing east-bound traffic, and designated by the letter "S" containing even exponents, will be operated to the stop position blocking east-bound traffic through the entire single track section, so that the west-bound train may proceed in accordance with the signal indications of the west-bound signals S⁵, S³, etc., which signals are controlled in a manner more particularly described herein-after with respect to the signals S⁴ and S⁶.

Let us now assume that an east-bound train has entered the single track section, which train by its entrance will of course through the tumble-down arrangement place the signals S³ and S⁵ in the stop position for reasons heretofore pointed out in connection with signals S⁴ and S⁶. As this east-bound train (moving from left to right) enters the block I, it causes deenergization of the winding CW⁴ of the signal S⁴ by reason of the opening of the contact 20 of the track relay T². As the train in question passes from the block I into the block J, it effects deenergization of the track relay T⁶. Dropping of the track relay T⁶ opens its contact 20¹ and closes its contact 30. Opening of the contact 20¹ effects deenergization of the control winding CW⁶ of the signal S⁶, which results in operation of the signal S⁶ to its danger position opening its contact 11.

Since the various pole changer relays, such as relay 6PC are slow acting, the pole changer relay 6PC will not assume its deenergized position until the stick relay 6S has been picked up through the following circuit:—beginning at the terminal B, back contact 30 of the track relay T⁶, wires 31 and 32, front contact 33 of the relay 6PC, wires 34 and 35, winding of the relay 6S to the other terminal (—). The stick relay 6S being quick acting closes its stick contact 36 very quickly and is thereby stuck up through the following stick circuit:—beginning at the terminal B, back contact 30 of relay T⁶, wires 31 and 37, stick contact 36 of relay 6S, wires 38 and 35, winding of the stick relay 6S to the other terminal (—). After a short period of time the relay 6PC will assume

its deenergized position and will provide another or auxiliary stick circuit for the relay 6S which may be traced through the back contact 33 of relay 6PC and the stick contact 36 of relay 3S, as readily traced in the drawing.

The provision of the two stick circuits, just mentioned, enables the use of a very quick acting stick relay, this because the stick relay, such as relay 6S, is held up through the stick circuit including back contact 30, while the relay 6PC 10 is moving from its energized to its deenergized position. As the east-bound train progresses the winding CW⁴ of the signal S⁴ is energized by current of negative relative polarity as soon as the rear end of the train under consideration 15 leaves the block I, this because the departure of the train from block I results in closure of the contact 16 of the track relay T⁵. With this contact closed current of negative relative polarity may flow through the winding CW⁴ through 20 the following circuit:—beginning at the lower terminal of the secondary winding of transformer 12, front contact 40 of the stick relay 6S, wire 41, back contact 14 of the relay 6PC, wire 14—A, contact 14—A1 of the stick relay 5S, 25 wire 15, contact 16 of track relay T⁵, wire 17, back contact 18 of stick relay 3S, wire 19, front contact 20 of track relay T², wire 21, winding CW⁴ of the signal S⁴, wires 22, C and 23 to the midpoint of the secondary winding of transformer 30 12. The completion of this circuit operates the signal S⁴ to the caution position (see Fig. 4) thereby giving a yellow caution indication to a train approaching the signal S⁴. It may be pointed out that the stick relays 3S and 5S are 35 part of the equipment associated with signals S³ and S⁵, respectively, and are controlled by their associated track relays and pole changer relays in a manner as has already been described in connection with the signal S⁶, and that the back 40 contact 18 of the stick relay 3S is a check contact, and prevents the signal S⁴ being cleared should the stick relay 3S be picked up falsely. The contacts 18 and 18¹ of these relays 3S and 5S, are therefore check contacts to assure that 45 conflicting signal indications cannot be set up at the same signal location. The slow acting pole changer relay, such as the relay 6PC, is necessary by reason of the quick acting spectacle operating mechanism of the light signal. For 50 instance, if the contact 33 of relay 6PC were operated directly by the mechanism of the signal S⁶ the stick relay 6S would probably fail to pick up for east-bound train movements, as has heretofore been described. The relay 6PC is 55 sufficiently slow acting to allow the stick relay 6S to pick up in response to dropping of the contact 30 of relay T⁶ before the contact 33 of the relay 6PC has moved from its attracted position.

Having thus shown and described one rather 60 specific embodiment of the present invention, it is desired to be understood that applicant's invention is not limited to the specific structure shown, except as demanded by the scope of the following claims.

What I claim is:—

1. In an absolute-permissive-block signaling system of the light signal type, a single track section, three-position light signals of the relay operated focal-plane spectacle type for governing 70 traffic in one direction, three-position light signals of the relay operated focal-plane spectacle type for governing traffic in the other direction, contacts on each signal operated in accordance with the spectacles thereof and closed in the 75

caution and clear positions of such signal, a slow acting relay for each signal operated by circuits including such contacts, a circuit for each signal including a front contact of the slow acting relay associated with the next signal in advance, a stick relay for each signal, a track circuit in advance of each signal and including a track relay, a pick-up circuit for each stick relay including a front contact of the associated slow acting relay and a back contact of the associated track relay, a stick circuit for each stick relay including a back contact of said slow acting relay and its own front contact, and an auxiliary circuit for each signal including a front contact of the stick relay of the next signal in advance.

2. In an absolute-permissive-block signal system, in combination, a three-position search-light type signal at each of several successive signal locations, a slow acting repeater relay for each signal energized if the associated signal assumes either the clear or the caution condition, a circuit for each signal energized by current of one polarity to operate such signal to the clear condition and closed if the repeater relay of the next signal in advance is energized, a stick relay for each signal, controlled by the repeater relay, and picked up and stuck up only in response to the movement of a train by such signal in the direction governed by such signal, and another circuit for each signal energized by current of another polarity to place the signal in its caution condition and closed only if the stick relay of the next signal in advance is energized and the repeater relay of the next signal in advance is deenergized.

3. In an absolute-permissive-block signal system, in combination, a three-position search-light type signal at each of several successive signal locations, a slow acting repeater relay for each signal energized if the associated signal assumes either the clear or the caution condition, a circuit for each signal energized to operate such signal to the clear condition closed if the repeater relay of the next signal in advance is energized, a stick relay for each signal picked up and stuck up only in response to the movement of a train by such signal in the direction governed by such signal, and another circuit for each signal energized to place the signal in its caution condition closed only if the stick relay of the next signal in advance is energized and the repeater relay of the next signal in advance is deenergized.

4. In an absolute-permissive-block signal system, in combination, a three-position search-light type signal at each of several successive signal locations, a slow acting repeater relay for each signal energized if the associated signal assumes either the clear or the caution position, a circuit including a line wire for each signal energized by current of one polarity to operate such signal to the clear position closed if the repeater relay of the next signal in advance is energized, a stick relay for each signal, controlled by its repeater relay, and picked up and stuck up only in response to the movement of a train by such signal in the direction governed by such signal, and another circuit including the same line wire for each signal energized by current of another polarity to place the signal in its caution position closed only if the stick relay of the next signal in advance is energized and the repeater relay of the next signal in advance is deenergized.

5. In an absolute-permissive-block signal system, in combination, a three-position search-

light type signal at each of several successive signal locations, a slow acting repeater relay for each signal energized if the associated signal assumes either the clear or the caution condition, a circuit for each signal energized to operate such signal to the clear condition closed if the repeater relay of the next signal in advance is energized, a stick relay having a pick-up circuit closed only if the block in advance of its associated signal is occupied, the pick up circuit including a front point of the repeater relay of the associated signal and a stick circuit including a back contact of said repeater relay, and another circuit for each signal energized to place the signal in its caution condition closed only if the stick relay of the next signal in advance is energized and the repeater relay of the next signal in advance is deenergized.

6. In an absolute-permissive-block signal system, in combination, a three-position search-light type signal at each of several successive signal locations, a slow acting repeater for each signal energized if the associated signal assumes either the clear or the caution position, a circuit for each signal energized by current of one polarity to operate such signal to the clear position closed if the repeater relay of the next signal in advance is energized, a stick relay having a pick-up circuit closed only if the block in advance of its associated signal is occupied and the repeater relay of the associated signal is still assuming its energized position and a stick circuit including a back contact of said repeater relay, and another circuit for each signal energized by current of another polarity to place the signal in its caution position closed only if the stick relay of the next signal in advance is energized and the repeater relay of the next signal in advance is deenergized.

7. In an absolute-permissive-block signal system, the combination with a three-position search-light type signal at each of several successive signal locations, of a slow acting repeater relay for each signal energized if the associated signal assumes either the clear or the caution position, a circuit for each signal energized to operate such signal to the clear position closed if the repeater relay of the next signal in advance is energized, a stick relay having a pick-up circuit closed only if the block in advance of its associated signal is occupied and including a front point of the repeater relay of the associated signal and two stick circuits one including a back contact of its associated repeater relay and the other including a contact closed only if the block in advance of its associated signal is occupied, and another circuit for each signal energized to place the signal in its caution position closed only if the stick relay of the next signal in advance is energized and the repeater relay of the next signal in advance is deenergized.

8. In an absolute-permissive-block signal system, in combination, a three-position search-light type signal at each of several successive signal locations, a slow acting repeater relay for each signal energized if the associated signal assumes either the clear or the caution position, a circuit for each signal energized by current of one polarity to operate such signal to the clear position closed if the repeater relay of the next signal in advance is energized, a stick relay having a pick-up circuit closed only if the block in advance of its associated signal is occupied and the repeater relay of the associated signal is still assuming its energized position and two stick
